UNITED STATES PATENT OFFICE.

DAVID S. JACOBUS, OF JERSEY CITY, NEW JERSEY, AND WILLIAM A. JONES, OF WEST NEW BRIGHTON, NEW YORK, ASSIGNEES TO THE BABCOCK & WILCOX COMPANY, OF BAYONNE, NEW JERSEY, A CORPORATION OF NEW JERSEY.

STEAM-BOILER ECONOMIZER.

1,313,991.

Specification of Letters Patent. Patented Aug. 26, 1919.

Application filed December 8, 1914. Serial No. 878,015.

To all whom it may concern:

Be it known that we, DAVID S. JACOBUS, a citizen of the United States, residing in Jersey City, in the county of Hudson and State of New Jersey, and WILLIAM A. JONES, a citizen of the United States, residing at West New Brighton, Staten Island, in the county of Richmond and State of New York, have invented certain new and useful

10 Improvements in Steam-Boiler Economizers, of which the following is a specification.

In an application Serial No. 784,315, filed August 12, 1913, by David S. Jacobus, is described a system by which liability of 15 corrosion of an economizer is prevented or minimized by first heating the feed water, then withdrawing it from the heating apparatus and permitting the greater part of the air or gases to escape before this water 20 is fed to the economizer or a part thereof. In that application the feed water is heated by passing it through the low pressure stage of a plural stage economizer and then delivered to a tank in which the greater part of 25 the air or gases is permitted to escape. From this tank the water is forced through the high pressure stage of the economizer against the boiler pressure, the high pressure stage being subjected to the hottest gases. 30 To meet the requirements of modern power plant practice of large size boiler units and high over-loads, a wrought iron or wrought steel construction was used for the high pressure stage of the economizer, such use 35 being permitted because of the practical elimination of the air and gases from the water before it is delivered to the high pressure stage. The present invention enables us to retain the use of cast iron for the low 40 pressure stage of the economizer, and thereby the advantage of the less liability of cast iron, over wrought iron or steel, to corrosion.

The present invention relates to a special 45 construction of a two-stage economizer adapted for use in the system described in the said application Serial No. 784,315, and will be understood by reference to the accompanying drawings in which Figure 1 is a 50 side view, partly in section of one form of economizer embodying our invention; Fig. 2 a top view, partly in section of the economizer of Fig. 1 with part of the covering removed, and showing also diagrammati-

55 cally, a tank for the removal of air and gases from the water after it passes through the low pressure stage; Fig. 3 a part longitudinal section on the plane of the line 3—3 of Fig. 5 through the low pressure stage of the economizer; Fig. 4 a transverse section 60 of the same, partly broken away on the plane of the line 4—4 of Fig. 5; Fig. 5 a top view of the low pressure stage, showing the direction of the flow of the feed water through the headers and tubes; Fig. 6 a transverse 65 section through one of the upper headers of Fig. 5; Fig. 7 a top view of a portion of one of the lower headers of the high pressure stage of the economizer; Fig. 8 a transverse section on the plane of the line 8—8 of Fig. 70 7; Fig. 9 a horizontal section on the plane of the line 9—9 of Fig. 10; and Fig. 10 an end view of the header and tubes of Fig. 8. Similar reference numerals indicate similar parts in the several views.

75 In the drawings the letter A designates generally the low pressure stage, and B the high pressure stage of the economizer which, in practice, will be located in the outlet flue of a steam boiler. The flow of the gases is 80 indicated by the arrow *a* in Fig. 2, the high pressure stage being subjected to the hottest gases and the low pressure stage to the coldest gases. The flow of the water through 85 the economizer is, in general, in the reverse direction of the flow of the gases. The low pressure stage is arranged in separated banks of vertical tubes, these banks being made up of groups of sections comprising 90 upper and lower headers and connecting tubes. As shown, there are three banks or groups of sections, the tubes and sections of the first bank being numbered in Fig. 3, 1 to 8 inclusive, those of the second, 9 to 16 inclusive, and those of the third section 17 to 95 24 inclusive. The tubes are arranged in rows, each row being connected to upper and lower headers, as hereinafter explained, and the tubes of one row staggered with respect to those of an adjoining row, in order 100 to prevent lancing of the gases and to expose all of the tube surfaces to the impinging gases. The feed water from the hot well, or any other source, enters the low pressure stage of the economizer through 105 the inlet 25 and is delivered to a manifold header 26 (Figs. 2 and 5), and from the latter the water is distributed to the

eight lower headers 27 of the first bank or group of sections, to which the lower ends of the tubes are connected. The water then flows upward from the headers 27 through 5 the tubes 1 to 8 inclusive to the upper headers 28 and from the latter through return bends 29 (Fig. 5) into a manifold header 30. The header 30 extends midway of the second bank or group of sections of the low pressure stage, and the water from the manifold header 30 is delivered through return bends 31 into four upper headers 32, the water passing from said headers 32 downward through 10 the four rows of tubes 9, 10, 11 and 12 to the lower headers 33 (Fig. 3) and from said latter headers to the lower manifold header 34 (Fig. 5) from which it is distributed to the four lower headers 35 (Fig. 3) of the second bank or group of sections, 15 and from thence upward through the tubes 13, 14, 15 and 16 to upper headers 36. From the headers 36 the water flows through return bends 37 (Fig. 5) to a manifold header 38 from which header it is delivered through 20 four return bends 39 to four upper headers 40 of the third bank or group of sections of the economizer, thence downward through tubes 17, 18, 19 and 20 of the third bank and is discharged into headers 41 (Fig. 3) and 25 thence to manifold header 42 (Fig. 5) from which it is distributed to four lower headers 43 from which it flows upward through tubes 21, 22, 23 and 24 to upper headers 44, through return bends 45 to manifold header 30 46 from which it is discharged through pipe 47. It is to be understood, of course, that 35 the invention is not limited to the exact number of sections in a group, or the exact number of sections or groups of sections or 40 method of circulation shown.

The spaces between the banks or groups of sections are wide enough for a workman to enter through access doors 48 (Fig. 1), and the width of each band is such that all 45 of the tubes are accessible. Doors 48' are provided at the sides and near the lowermost ends of the tubes. The doors 48 and 48' are preferably of cast iron, asbestos packed and lined, and fitted with cast iron frames. Be- 50 neath each of the banks or groups of sections are hoppers 49 for collecting soot deposited from the gases and that removed from the exterior of the tubes by scrapers 50 hung by chains over wheels 51. The latter are 55 geared to a shaft 52 adapted to be rotated in both directions to raise and lower the scrapers along the tubes. When the doors 48' are open the lower ends of the tubes of the low pressure stage of the economizer 60 are exposed throughout the entire length of the low pressure stage, giving accessibility for cleaning the lower ends of the tubes from the sides of the economizer by means of a scraper or other tool. This is an especially 65 desirable feature as with water fed to the

economizer directly from the hot well at a temperature of say 80° F. there will be condensation or sweating on the outside of some of the tubes of the low pressure stage, and this causes the dust and soot which falls 70 to the lower ends of the tubes to become cemented to the tubes and to the lowermost headers. The cleaning doors give ready access, without cooling down the economizer, for removing this material which otherwise 75 would bridge over between the headers and eventually interfere with the operation of the scrapers and the efficiency of the apparatus.

The doors 48 and the spaces between the banks permit a workman to enter between the banks of tubes and provide for access to the full length of the tubes for coating the tubes with paint, or other material, to prevent or minimize external corrosion. 80 Even when the scrapers 50 are used the low pressure stage should be arranged for access as a pasty material may cling to the lower ends of the tubes and above the lower headers, and by providing access between 85 the banks and at the ends of the sections, and by making the banks of such a number of sections that all of the tubes can be reached, this material may be removed by hand when the boiler is shut down. Should any of 90 the fumes or vapor, condensed from the gases drop from the lowermost headers, it will fall into the hoppers 49. The moisture in the soot and dust which falls into the hoppers 49 will be evaporated under ordinary running conditions as the gases which circulate slowly through the hoppers are 95 hotter than the surfaces of the economizer tubes. The soot and dust are removed through suction discharge pipes 53 and 54. 100

The three manifold headers 26, 34 and 42, shown in Figs. 2 and 5, have connections 55, 56 and 57 respectively to a common blow-off main 58, shown in Fig. 3.

In Fig. 6 is shown the usual construction 110 employed in cast iron economizers for connecting the tubes with the headers. The headers 28, 32, 36, 40 and 44 are similar in construction. As shown, they are provided with handhole plates 64 which are drawn 115 to their seats by bolts 65 and brace 66.

From the low pressure stage of the economizer the water flows through pipe 47 to a tank or heater 59 (see Fig. 2) in which tank the air and non-condensable gases are 120 permitted to escape into the atmosphere through a relief valve or vent pipe 59', or are withdrawn through a pipe 60 connected to a dry vacuum pump to maintain the pressure above the water in the tank at 125 less than atmospheric pressure. Any other suitable means may be employed for maintaining a partial vacuum in the tank 59. The tank 59 is provided with a blow off connection 59² for removing any mud or 130

deposit. A filter 59³ is placed in the tank 59. From said tank the water is delivered through a pipe 61 to a pump 62, and by the latter forced through pipe 63 into and through the high pressure stage of the economizer against the boiler pressure.

The high pressure stage of the economizer, as shown, consists of ten similar sections, each section consisting of a lower header or box 67 and an upper header or box 68, connected by two rows of vertical tubes 69 arranged in staggered relation, as shown more particularly in Fig. 7. As shown in Figs. 1 and 2 each upper header is connected 10 to the lower header of the next section by a series of inclined tubes 70 so that the water from pump 62 enters the high pressure stage through the left-hand lower header 67, flows upward through the tubes 69 of that section to the upper header 68 and thence downward through the inclined tubes 70 between the first and second sections to the lower header 67 of the second section. Thence through the vertical tubes 20 15 of the second section to the upper header of that section, thence downward through the inclined tubes to the lower header of the third section and so on through all of the sections to the top outlet 71 from whence 25 it is led to the boiler. As shown in the drawings (see Fig. 2) the inclined tubes connecting the upper header of one section to the lower header of the next succeeding section are fewer in number than the tubes in 30 35 the vertical rows.

The circulation in the high pressure stage of the economizer is novel in that, the water enters the bottom of each section, passes upward through the tubes of that section, and then downward to the bottom of the 40 next succeeding section. About every tenth tube is expanded into the upper box of one section and into the lower box of the next section forming the inclined 45 downcomers 70 for conveying the water from one section to the next succeeding section. The advantage of this construction is that the water is maintained at a comparatively high and uniform velocity through 50 the economizer, thus making it possible to sweep away any bubbles of air or non-condensable gases which may collect on the inside of the tubes. This is accomplished by using a less number of downcomers for conveying the water from one section to another than there are vertical tubes through 55 which the water flows upward. The dislodgment of bubbles of air or non-condensable gases through the flow of the water is 60 particularly effective with the arrangement described, as where the water is made to flow downward the velocity is high, in order that it shall overcome the tendency of the bubbles to rise through the water and provide 65 an additional impetus to sweep them

from the surface of the tubes and carry them downward along with the water. Where the water rises through the tubes the buoyancy of the bubbles assists in releasing them from the surface of the tubes and 70 it is not necessary to maintain as high a velocity as where the flow is downward. After the air or non-condensable gases reach the upper part of a section they are bled to the next section by vent connections 72 75 (Fig. 2) formed by connecting each uppermost box with one at its side by a pipe of relatively small diameter. These connections are attached to the ends of each upper box and are arranged so that any air or non-condensable gas which may be present will 80 pass from box to box traversing the full length of each box in its passage from one end of the economizer to the other. In addition to the vent connection for passing the air or non-condensable gases from one box to another, each upper header of the high pressure stage is provided with air valves 73 (Fig. 2) which can be opened to allow the air to escape in filling the economizer 85 with water, or which may be opened when drawing water from the economizer.

With the method of circulation described the water flows successively through each section and the temperature of the water is 90 gradually increased from section to section from one end of the high pressure stage to the other; this leads to a maximum efficiency in the absorption of heat.

It may be further noted that the described 100 arrangement avoids a stagnation in the flow of water in any of the tubes of the high pressure stage, as the water flows upward through a large number of tubes, and if any one of these tubes should become heated 105 to a temperature higher than that of the other tubes of the same section, the water in the hotter tube would be less dense than that in the other tubes of the same section, and would offer less resistance to the upward 110 flow of water, and, therefore, a greater quantity of water would immediately flow through the hotter tube and this would cool the tube and restore the equilibrium of flow through the tubes of that particular 115 section.

A relatively few tubes conduct the water downward from the upper header of one section to the lower header of the following section. If any one of the tubes 70, 120 through which the water flows downward from a given section, should become heated above the temperature of the other tubes, 70, of that section, the water in the hotter tube would become less dense and would 125 offer a greater resistance than the others to the downward flow of the water, which would at once tend to increase the temperature of the hotter tube still further. This tendency to localize the flow of water 130

through one or more of the downcomer tubes is overcome by employing a small number, which makes the frictional resistance within the tubes relatively high, so that the increase 5 in friction due to a slight increase in the quantity of water flowing through one tube over another, is greater than the difference in resistance due to differences in the temperature of the water, and thus the water is 10 made to divide itself properly among the downcomer tubes.

Although we have described the flow of the water up and down the tubes from section to section in series, a small amount of 15 the water is by-passed from one section to the next through the small pipe connections 72 used for conveying the air and non-condensable gases from one header box to the next. As already explained the vent connections 20 are so arranged that the air and gases enter one end of each upper box and leave at the other end of the same box, traveling the length of the box. This is advantageous in preventing a direct short 25 circuiting of the water which might take place by having all of the vent connections on one side of the economizer, and it avoids the possibility of the air and non-condensable gases collecting in dead spaces in the 30 boxes. Any water which flows through the vent connections 72 along with the gases from one box to the next mingles with the water in that box before entering the succeeding vent connection and in this way 35 there is no opportunity for the cooler water from the inlet end of the economizer to pass directly into the hotter water at the exit end of the economizer.

The high pressure stage is provided, as 40 shown in Fig. 1, with individual blow-off valves 77 and connections 78 for each lower-most header. This is especially advantageous as by blowing off each header separately a high velocity can be secured through the 45 headers which makes it possible to carry away any sediment much more efficiently than where there is a single blow-off for a number of headers. We also provide openings 81 in the top of the casing for the high pressure 50 stage (see Figs. 1 and 2) for the introduction of an air or steam lance between the boxes for dusting the outside of the tubes.

In addition to the cross passages for a 55 workman to enter between the banks or groups of sections of the low pressure stage, there is a similar cross passage between the low pressure stage and the high pressure stage, these cross passages affording access to the tubes as before described.

60 In Figs. 1 and 3 we have shown vertical diaphragms 79 in the soot hoppers 49 to prevent short circuiting of the gases underneath the low pressure stage, and transverse channels 80 forming flooring partially filling 65 in the spaces between groups of headers of

the low pressure stage, and between the low pressure stage and the high pressure stage. These channels are shown as narrower than the spaces in which they are placed so that there is an opening at each side of each channel to permit dust to fall down into the hoppers. 70

In addition to the foregoing features of construction we have shown more particularly in Figs. 7 to 10 the means by which the 75 tubes of the high pressure stage may be expanded into the upper and lower headers. As there shown, opposite each tube in the square headers or boxes are inside hand-hole fittings 74 to permit examination, cleaning 80 and expanding the tubes. The hand-hole openings 75 are of less diameter than the tube holes 76, and the tubes cannot be passed through the openings opposite them in the boxes. The tubes are removed and replaced, 85 when desired, by passing them downward through the spaces between the boxes, clearly indicated in Fig. 2, and slipping one end of the tube through the hole in one of the boxes, and then moving the tube in the reverse direction through the hole in the opposite box. This method of introducing the tubes has an 90 advantage, in that, as much head room is not required for removing and replacing tubes as in a construction where they must 95 be drawn upward through holes in the headers or boxes which come opposite the tubes. The hand-hole fittings 74 are circular and are made tight by means of gaskets, and by means of a cross piece and nut which come 100 outside of the boxes. They are passed inside the boxes through the oval hand-holes 76 at the end of the boxes.

It will be understood that we intend to cover the construction and arrangement 105 shown in each stage, whether such construction is used by itself in a single stage economizer or in a multiple stage economizer.

What we claim and desire to secure by Letters Patent of the United States is:— 110

1. A steam boiler economizer comprising a plurality of sections each section having a single upper and a single lower cross box connected by vertically extending upflow economizer tubes, each upper box having depending downflow tubes spaced along the length of the box and connecting it to the lower box of the next section, the cross sectional area of these down flow tubes being less than the cross sectional area of the up 115 flow tubes to the upper box, and the down flow tubes forming part of the heating surface. 120

2. A steam boiler economizer comprising a plurality of sections each section having a single upper and a single lower cross box connected by vertically extending upflow economizer tubes, each upper box having depending downflow tubes spaced along the length of the box and connecting it to the 125 130

- lower box of the next section, the cross sectional area of these down flow tubes being less than the cross sectional area of the up flow tubes to the upper box, the down flow tubes forming part of the heating surface, all of the tubes of each section, including the down flow tubes from the upper box to the lower box of the next section, being staggered relatively to each other.
- 10 3. A steam boiler economizer composed of a series of sections each section having a single upper box and a single lower box connected by vertically extending tubes, each upper header of each section having a by-pass connection leading to the upper header of the next section for conveying air or non-condensable gas through the successive upper headers.
- 15 4. A steam boiler economizer composed of a series of sections each section having a single upper box and a single lower box connected by vertically extending tubes, each upper header of each section having a by-pass connection leading to the upper header of the next section for conveying air or non-
- 20
- 25

condensable gas through the successive upper headers, and each of the by-pass connections having an air escape valve.

5. A steam boiler economizer composed of a series of sections each section having a single upper box and a single lower box connected by vertically extending tubes, each upper header of each section having a by-pass connection leading to the upper header of the next section for conveying air or non- 30 condensable gas through the successive upper headers, said by-pass connections being arranged to compel the air and gas to traverse the entire length of each of the upper headers in their passage from one end of the 35 economizer to the other.

In testimony whereof we have hereunto signed our names in the presence of two subscribing witnesses.

DAVID S. JACOBUS.
WILLIAM A. JONES.
